UNITED STATES PATENT OFFICE

171,011

COASTER WAGON WHEEL

Paul H. Rosenberg, Lansing, Mich., assignor to
Reo Motors, Inc., Lansing, Mich., a corporation
of Michigan

Application December 26, 1951, Serial No. 17,823

Term of patent 14 years

(Cl. D34—15)

To all whom it may concern:

Be it known that I, Paul H. Rosenberg, a citizen of the United States, residing in the city of Lansing, in the county of Ingham, State of Michigan, have invented a new, original, and ornamental Design for a Coaster Wagon Wheel, of which the following is a specification, reference being had to the accompanying drawing, forming a part thereof, wherein:

Fig. 1 is a front elevational view of a coaster wagon wheel, showing my new design;

Fig. 2 is an end elevational view thereof; and

Fig. 3 is a cross-sectional view thereof, taken substantially on line 3—3 in Fig. 1.

I claim:

The ornamental design for a coaster wagon wheel, as shown and described.

PAUL H. ROSENBERG.
